United States Patent Office

Des. 184,531
Patented Mar. 3, 1959

184,531

STORAGE BATTERY CONTAINER

Van Nelson, Monterey Park, Calif.

Application October 8, 1958, Serial No. 52,899

Term of patent 14 years

(Cl. D26—6)

The single figure is a perspective view of a storage battery container, showing my new design. The back and opposite end, not shown, are substantially mirror images of the front and end shown.

I claim:

The ornamental design for a storage battery container, as shown and described.

UNITED STATES PATENT OFFICE
CERTIFICATE OF CORRECTION

Design No. 184,531

March 3, 1959

Van Nelson

It is hereby certified that error appears in the above numbered patent requiring correction and that the said Letters Patent should read as corrected below.

In the grant, lines 1, 2 and 3, for "Van Nelson, of Monterey Park, California," read -- Van Nelson, of Monterey Park, California, assignor to Stauffer Chemical Company, a corporation of Delaware, --; line 13, for "Van Nelson, his heirs" read -- Stauffer Chemical Company, its successors --; in the heading to the drawing and specification, line 3, for "Van Nelson, Monterey Park, Calif." read -- Van Nelson, Monterey Park, Calif., assignor to Stauffer Chemical Company, a corporation of Delaware --.

Signed and sealed this 21st day of July 1959.

(SEAL)
